Primary Examiner—C. A. Murphy*Attorney, Agent, or Firm*—Aquilino & Welsh[57] **CLAIM**

The ornamental design for a shirt for the sport of paint ball, as shown and described.

DESCRIPTION

FIG. 1 is a front perspective view of a shirt for the sport of paint ball showing my new design, the broken lines shown in both views being understood to represent conventional stitching; and,

FIG. 2 is a rear perspective view thereof, the wrist closures shown fastened.
